PRODUCTION OF WARP KNITTED FABRICS

Paul Schönfeld, Chemnitz, Germany

Application July 20, 1939, Serial No. 285,495
In Germany July 23, 1938

3 Claims. (Cl. 66—86)

This invention relates to the production of warp knitted fabrics provided with rubber warp threads which form meshes in spots.

It has been proposed to produce fabrics of this class, which comprise two textile thread groups between which rubber threads are worked in so as to form meshes in places to prevent them from running back.

According to another proposal relating to two-machine warp fabric in which the upper thread group is wholly or partly interlaced without forming meshes the threads of this upper group of textile threads form meshes also in the courses following those in which the rubber threads form meshes. The heads of the rubber thread meshes are thus caught by the feet of these meshes of the upper textile thread group, provided the latter is worked in a specific manner, which may sometimes be undesirable with respect to patterning or for other reasons. Furthermore, the rubber thread meshes cannot be caught at all unless the rubber warp threads are positioned between two textile thread groups, and the proposal does therefore not apply to warp knitted fabric comprising only a single textile thread group.

The object of the invention is to overcome the difficulties mentioned in the production of warp knitted fabric of this type by lapping the rubber threads in the courses following those in which they form meshes over two needles in a mesh-forming manner so that the head of the rubber thread meshes formed first is caught by the mesh, arranged in the same wale, of the two superposed rubber thread meshes.

In this way, the rubber threads themselves are caused to hold the meshes formed by them and are thus fully secured against running back without requiring special means, particularly because the tying action of the catching mesh of the pairs of rubber thread meshes is enhanced with respect to the rubber thread meshes caught by the rubber thread mesh adjacent to the catching mesh. Owing to this multiple tying or interlacing the rubber thread is effectively prevented from stretching which easily occurs if the meshes are tied only in the known manner.

The invention is illustrated by way of example in the accompanying drawings, in which

Figure 1 is a lapping diagram and

Fig. 2, a diagram of mesh formation in a fabric made according to the invention.

The textile threads 1 gathered in the lower lapping machine form the warp fabric into which rubber warp threads 2 are worked by being

laterally racked to insure their tying up in the single machine fabric. Furthermore, to prevent them from running back the rubber warp threads 2 are formed into meshes in spots simply by being guided once around their needles in the courses concerned, i. e., in the courses 3 in the example shown. The rubber threads 2 are then lapped again over two needles in a mesh forming manner in the following courses 4 with the result that the head of the first formed rubber thread meshes is held in the finished fabric by the feet of the respective mesh of these two rubber thread meshes formed in the courses 4.

The course of the rubber warp threads between these mesh forming points and the manner of lapping are of secondary importance. The invention can of course be applied also to warp knitted fabrics comprising two or more textile thread groups.

It is evident that the double meshes of the rubber warp threads 2 in the courses 4 can catch or hold the single meshes of rubber threads of the courses 3 only if these single rubber thread meshes are properly formed. This requires that the rubber threads 2 are introduced during lapping into the courses 3 in racking direction at least one needle in front of the needles that have to be surrounded to form single rubber meshes. In the example shown this point of introduction of the rubber warp threads 2 is positioned two needles in front of the needles producing these single rubber thread meshes and from the points of introduction to the last-mentioned needles the rubber threads 2 are lapped by an underlaying operation. The same arrangement is to be followed if the rubber warp threads are to be worked into the fabric exclusively in the form of single meshes.

It is, moreover, advantageous to rack the rubber warp threads 2 laterally in the same direction in which racking of the lower thread group 1 occurs, at least for forming single meshes, i. e., in the courses 3. If a fabric is to be produced which is formed only from a textile thread group 1 as shown, the rubber warp threads 2 are preferably laterally racked always in the same direction as the threads 1 to prevent distortion of the finished goods.

I claim:

1. A method of producing warp knitted fabric provided with rubber warp threads which form meshes in spots, consisting in lapping the rubber threads in the courses following those in which they form meshes over two needles, in mesh-forming manner and thereby causing the head

50

55

of the first formed meshes to be caught by the mesh, arranged in the same wale, of the two superposed rubber thread meshes.

2. A method according to claim 1, in which during lapping of the single rubber thread meshes the rubber warp threads are introduced in racking direction into the courses concerned at least one needle in front of the needles to be surrounded to form these single meshes and from the point of introduction to the needles producing the rubber thread meshes are lapped in the form of an underlaying operation.

3. A method according to claim 1, in which

during lapping of the single rubber thread meshes the rubber warp threads are introduced in racking direction into the courses concerned at least one needle in front of the needles to be surrounded to form these single meshes and from 5 the point of introduction to the needles producing the rubber thread meshes are lapped in the form of an underlaying operation and in which the rubber thread group, at least for forming single meshes, is laterally racked in the same 10 direction as the ground thread group.

PAUL SCHÖNFIELD.
